(57) **CLAIM**

The ornamental design for a tandem type rod end, as shown and described.

DESCRIPTION

FIG. 1 is a front elevational view of a tandem type rod end, showing our new design;

FIG. 2 is a rear elevational view thereof;

FIG. 3 is a top plan view thereof;

FIG. 4 is a bottom plan view thereof;

FIG. 5 is a left side view thereof;

FIG. 6 is a right side view thereof; and,

FIG. 7 is a perspective view thereof.

This article is related to a tandem type rod end that constitutes a steering damper for a vehicle.
